United States Patent Office

Des. 180,175
Patented Apr. 30, 1957

180,175

SPOON OR SIMILAR ARTICLE

Henry N. Bull, Forest Hills, N. Y.

Application August 17, 1955, Serial No. 37,538

Term of patent 14 years

(Cl. D44—29)

Fig. 1.

Fig. 2.

Fig. 1 is a perspective view of a spoon or similar article, embodying my new design;

Fig. 2 is another perspective view from a different angle;

Fig. 3 is an elevational view, and

Fig. 4 is a sectional view taken along the line 4-4 of Fig. 3.

The essential features of the design reside in the handle shown in solid lines in the drawings.

I claim:

The ornamental design for a spoon or similar article, substantially as shown and described.
